UNITED STATES PATENT OFFICE.

WILLIAM H. NEWELL, OF WILLIAMSBURG, MASSACHUSETTS.

INJECTOR.

SPECIFICATION forming part of Letters Patent No. 283,013, dated August 14, 1883.

Application filed May 28, 1883. (Model.)

To all whom it may concern:

Be it known that I, WILLIAM H. NEWELL, of Williamsburg, in the county of Hampshire and State of Massachusetts, have invented a new and useful Improvement in Injectors, of which the following is a specification.

The objects of this invention are, first, to render an injector self-regulating for variations in steam and water pressures, so that in spite of such variations the injecting force shall remain constant; second, to augment this injecting force to an extent greater than usual in injectors; and, third, to deliver the water to the boiler at the boiling-point of temperature, utilizing the heat of the steam used in operating the injector for this purpose. I accomplish this by adding to the steam-pressure for forcing the water into the boiler the pressure of a portion of the injected water which is separated from the rest and carried to a point behind the steam-jet, and, passing through a nozzle surrounding the steam-jet nozzle, is projected into the combining-tube with such force as to greatly assist the steam-jet in forcing the water into the boiler, and to compensate for any variations in the water-column or steam-jet pressure. The water, becoming heated in this process by its contact or contiguity with the injecting steam, is delivered into the boiler at the boiling-point of temperature. In addition to this arrangement I may provide a tube extending from the injector-tube back into the water-pipe, the end of such tube extending to the narrow jet or opening, which in this case forms the junction between said water-pipe and the water-chamber. Water is forced through this tube and enters the water-chamber with such force as to assist in propelling the water in the chamber through the combining-tube. This also assists in heating the water in the chamber.

In the accompanying drawings, Figure 1 is a longitudinal vertical section of an injector embodying the invention, (the modification above described being shown in dotted lines,) and Fig. 2a transverse vertical section thereof.

A is the water-chamber, to which are connected the water-pipe B and the steam-pipe D. E is the overflow-valve.

Extending inwardly from the pipe D is the steam-jet nozzle F, opposite to the end of

which is the mouth of the combining-tube G. The steam-nozzle F is provided with ribs or projections a.

H is a nozzle encircling the steam-nozzle F. 55 This is held between the part b of the water-chamber and the ribs or projections a of the steam-jet nozzle, a chamber, I, being thus formed between the nozzle H and the enlarged portion c of nozzle F. From this chamber I 60 a water-passage, J, extends to the injector-tube C, which communicates with the boiler. The overflow-valve E is connected with this passage J.

The combining-tube G is flanged at d, and is 65 held against the wall of the water-chamber A by a nut, e.

The injector-tube C is secured to the body of the apparatus by the ring K.

The operation of this apparatus is as follows: Water is admitted to the water-chamber A through the pipe B, the overflow-valve E being open, and passes through the combining-tube G and through passage J to the valve, the injector being always used in connection 70 with a sufficient head of water to cause this rise in the water column. Steam is now admitted to the nozzle F and the valve E closed. The jet of steam forces the water which it encounters through the combining-tube and toward the boiler. A portion of the water, however, passes through the passage J to the chamber I and encircling nozzle H, and, being under pressure, is projected through such encircling nozzle into the combining-tube, its 75 force being added to that of the steam-jet in forcing the feed-water through such tube into the boiler. The additional power thus obtained causes the water to be injected into the boiler with greater force than usual. The water, being reheated by its contact with the steam-jet, enters the boiler at its maximum 80 temperature, and the heat of the steam used in operating the injector is thus utilized instead of being wasted, as is usually the case. 85

The pipe M may or may not be used in connection with the apparatus already described. If it is used, the water-inlet to the chamber A is formed into a narrow jet at m, and the pipe M extends to this opening. Water from the 90 injector-tube is thus returned under pressure to the water-chamber A, and assists in forcing

the water through the combining-tube and in heating the water in the pipe B and in the chamber.

What I claim is—

- 5 1. The method of operating feed-water injectors, consisting in re-enforcing the steam-jet pressure by the force of a portion of the water returned from the injector-tube to behind the combining-tube, substantially as set forth.
- 10 2. The method of operating feed-water injectors, consisting in returning water to the steam-jet after passing through the combining-tube and reforing it through said tube, substantially as set forth.
- 15 3. In an injector, the combination, with the steam-jet and the combining-tube, of a water-passage for returning the water from beyond the combining-tube to behind the steam-jet, substantially as set forth.
- 20 4. In an injector, the combination, with the steam-jet nozzle and the combining-tube, of a nozzle encircling said steam-jet nozzle and a passage leading from beyond the combining-tube to said encircling nozzle, substantially as set forth.
- 25 5. The combination, with the water-chamber, the injector-tube, and the combining-tube uniting them, of a passage leading from said injector-tube to behind the steam-jet nozzle and a water-nozzle encircling said steam-jet nozzle, substantially as set forth.
- 30 6. The combination of the steam-jet nozzle having an enlarged portion, c, the encircling

water-nozzle provided with a flange, and the chamber formed between said enlarged portion and said flange, substantially as set forth.

35 7. The combination, with the chamber I, formed between the steam-jet nozzle and the encircling water-nozzle, of the passage leading from said chamber to the injector-tube beyond the combining-tube, substantially as set forth.

40 8. The combination of the water-chamber, the encircling water-nozzle, and the projections or ribs on the steam-jet nozzle for holding said encircling nozzle against said water-chamber, whereby the chamber I is formed behind said encircling nozzle, substantially as set forth.

45 9. The combination, with the water-passage leading from the injector-tube to the chamber I, of the overflow-valve communicating with said passage, substantially as set forth.

50 10. In an injector, a tube extending from the injector-tube to the water-inlet, substantially as and for the purpose set forth.

55 11. The water-inlet provided with a jet-orifice opening into the water-chamber, in combination with a tube extending from the injector-tube to said orifice, substantially as set forth.

60 This specification signed and witnessed this 8th day of May, 1883.

WILLIAM H. NEWELL.
